 G. Stone, doing business as Manchester Hosiery
 Mills, Manchester, N. H.

Application May 19, 1952, Serial No. 19,776

Term of patent 14 years

(Cl. D47—7)

To all whom it may concern:

Be it known that I, Abraha Wilcher, a citizen of the United States, residing at Manchester, New Hampshire, have invented a new original, and ornamental Design for a Lady's Stocking, of which the following is a specification, reference being had to the accompanying drawing, forming a part thereof, in which:

Figure 1 of the drawing is a fragmentary perspective view of a lady's stocking, showing my new design, as seen from the rear of the stocking looking at the heel section and sole.

I claim:

The ornamental design for a lady's stocking, as shown.

ABRASHA WILCHER.
